Patented Dec. 8, 1914.

FIG. 1.

UNITED STATES PATENT OFFICE.

JOHN GUNNAR LINDMARK, OF ESKILSTUNA, SWEDEN, ASSIGNOR TO ESKILSTUNA
STÅLPRESSNINGS AKTIEBOLAG, OF ESKILSTUNA, SWEDEN.

FLOATING SUBMARINE MINE.

1,120,621.

Specification of Letters Patent.

Patented Dec. 8, 1914.

Application filed August 14, 1914. Serial No. 856,837.

To all whom it may concern:

Be it known that I, JOHN GUNNAR LINDMARK, a subject of the King of Sweden, and a citizen of Sweden, residing at Eskilstuna, 5 in the Kingdom of Sweden, have invented certain new and useful Improvements in Floating Submarine Mines, of which the following is a specification.

The present invention has reference to 10 improvements in torpedo mines, driving mines and other similar submarine bodies and has for its object to give them a periodical up-and-down movement in the sea and thus keep them floating at a desired 15 middling depth below the water surface, until after a determinated period of time, the mine sinks to the bottom of the sea and thus becomes inoffensive. Said periodical up-and-down movement is effected by altering 20 the displacement of the submarine body (the mine). The alteration is caused by means of a periodical taking-in of water and letting-out the same from a vessel placed within the mine. The in- and outlet 25 is controlled by a hydrostatic device and is effected by means of compressed air or some other gas. The air or the gas is stored in a suitable pressure vessel and periodically supplied to the vessel within the mine, the 30 so called regulating vessel, whereby water is expelled or supplied to the said vessel.

The present invention has now for its object to control the admission of air or gas at each deep-swinging, so that always a predetermined 35 gas volume be supplied to the regulating vessel, and is chiefly characterized thereby, that between the pressure- and regulating vessel is inserted an intermediate vessel, by which the volume of air or gas to 40 be supplied to the regulating vessel is determined.

A form of execution of the invention is illustrated on the annexed drawing, where—

Figure 1 as an illustration shows a spherical mine in vertical section according to the 45 present invention and Figs. 2 and 3 show details on a larger scale.

1 is the outer casing of the mine, said casing being suitably of spherical or cylindrical shape and provided at the top with a cover 2. In said cover is placed a hydrostatic apparatus, which may be of any type preferred, but which on the drawing is of the known type used in the Whitehead torpedo. The apparatus is thus provided with

a hydrostatic plate or piston 3, on the outside covered by a rubber plate 4 and on the inside acutated upon by a spiral spring 5. Said spring, the so called depth-controlling spring, can by means of a straining piece 6 be strained more or less according to the middling depth on which the mine is to be kept floating. The displacement of the straining piece 6 is effected by means of a rod 8, pivoted in loops on the spring-casing 7, the opposite end of said rod 8 being pivotally connected to a nut 9. Said nut can be moved up and down on a screw 10, turnably mounted in cover 2. The screw 10 can be turned around from the outside of the mine by means of a tool, whereat the nut 9 is moved in the one direction or other and the spring 5 by means of the rod 8 and the straining piece 6 is strained or expanded. The strain of said spring 5 can be observed from the outside.

The movement of the hydrostatic piston in the one direction or the other under influence of the outer water-pressure, or the spring-pressure, is transmitted to the piston valve 12 by means of a rod 11 mounted in a frame, said piston valve being movable in a valve box 13. Said piston valve 12 serves to control the admission of the compressed air used for the regulating of the depth of the mine. The compressed air is inclosed under high pressure (for inst. 100 to 150 atm.) in a vessel 14, provided with a filling valve 15 for charging the vessel from the outside of the mine and with a closing valve 16, by means of which the escape of the air from said vessel 14 can at will be controlled from the outside of the mine. The filling and closing valves may also suitably be of the types used in the Whitehead torpedo.

From the vessel 14 the highly compressed air is conducted through the tube 17 to a pressure regulator 18 being likewise of known construction. Said regulator is preferably placed so that it may be adjusted from the outside of the mine. In the pressure regulator the pressure of the air is lowered to a predetermined, constant amount, for inst. 10 to 15 atm. whereupon it passes on farther through the pipe 19. This pipe branches off into two tubes, 20 and 21, of which tube 20 conducts to the valve box 13 and the tube 21 leads to another valve box 22 inclosing a relay-piston valve 23, the function of which will be described below.

24 is a regulating vessel, which communicates with the water surrounding the mine partly by a tube 25, leading directly from the surface of the mine to the lower end of the regulating vessel and partly through tube 26, connecting the regulating vessel to the box 20 of the relay piston valve. Said box is in its turn by means of tube 27 in communication with the water surrounding the mine. Tube 26 issues from a screw-neck on the upper end of the regulating vessel. In this neck there is screwed in a tube 28 extending into the regulating vessel. The said tube can be turned around by means of a shifter, in order to extend more or less into the regulating vessel. Hereby the mouth of tube 26 is brought to project more or less into the regulating vessel.

From the valve box 13 two tubes 29, 30 are extending, each connected to one end of the valve box 22. From the said box extends still another tube 31 communicating with a smaller vessel 32, the so called intermediate vessel.

25 The piston valve 12 has two valve-faces 33 and 34 and at each end a tightening-piston. Between said valve-faces and tightening-pistons the piston valve body is turned off to form three smaller parts 35, 36, 37. When said piston valve 12 is in its lowermost position (Fig. 2), the air supply tube 20 is in communication with tube 30 through the space surrounding the part 36, whereas tube 29 communicates with the outlet opening 38, through the space surrounding the part 35. At the opposite upper end-position (Fig. 3) tube 29 is in communication with the inlet tube 20, whereas tube 30 is in communication through the space surrounding the part 37 with the outlet 39. The relay piston valve 23 has likewise two valve faces 40, 41 and two tightening pistons, between which are situated the turned off parts 42, 43, 44. The mouths of tubes 26 and 31 in the relay piston valve box are both extending by means of grooves 45, 46, running in the length direction of the piston valve. Between the mouths of tubes 21 and 27 in the relay piston valve box there is a lengthwise-running groove 47, separated from said mouths.

When the relay piston valve is moved to its end position, corresponding to the lowest position (Fig. 2) of the piston valve 12, the tube 21 communicates through the space surrounding the part 44 with tube 31. At the same time tubes 26 and 27 communicate with each other through the space surrounding the part 42.

60 At the opposite end position, corresponding to the upper position of slide 12 (Fig. 3) the communication between the tube 21, 31 is interrupted by one of the tightening pistons. The communication between the tubes 26, 27 is likewise interrupted by the

valve-face 40. On the other hand, communication is established between the tubes 26 and 31 through the grooves 45, 47, 46 and the spaces surrounding the parts 43, 44.

The function of the mine is as follows: 70 Previous to the throwing out or shooting off of the mine the air vessel 14 is filled with highly compressed air and the closing valve 16 is opened. The pressure regulator 18 is adjusted for a determined pressure and the depth regulating apparatus is adjusted for the desired middling depth. The highly compressed air then passes through tube 17 to the pressure regulator 18, in which the pressure is reduced, and air of reduced pressure is conducted through tube 19 and its branches 20 and 21. When the hydrostatic piston 3, now actuated upon by the pressure of the spring 5, occupies its outmost position, the piston valve 12 is in its lowest position and the low-compressed air entering through tube 20 passes through the space surrounding the part 36 and further through tube 30 to the box 22 of the relay piston valve moving same to the end position 80 shown in Fig. 2. The opposite end of the relay-piston valve is on the other hand subjected to the pressure of the escaping air because the tube 29 is in communication with the outlet opening 38 through the space surrounding part 35, said outlet opening 38 being either in communication with a separate outflow-vessel or opens directly to the interior of the mine. The air has now free passage between the tubes 26 and 27 through the space surrounding the part 42 of the relay piston valve and the space surrounding the part 44 between tubes 21 and 31. The low-compressed air now passes from the tube 19 through the latter tubes into the intermediate vessel 32, filling it with air of the reduced pressure. This is the state of the mine when it strikes the surface of the water. As the mine is beforehand weighed off to about the same specific weight as the water, it begins immediately to sink until quite submerged under the surface of the water. Hereby the water rushes in through tube 25 to the regulating vessel 24, expelling air through the tubes 28 and 26, the space surrounding the part 42 of the relay piston valve and the tube 27. The displacement of the mine being thus decreased the mine sinks still more. The hydrostatic piston is thereby simultaneously pressed inward owing to the increased water-pressure, and when the mine reaches the desired middling-depth, the hydrostatic piston and the valve piston 12 are in the middle position. The mine continues to sink, however, whereby the piston is pressed still more inward and the piston valve 12 is raised, giving admission to the low-pressure air from the tube 20 through the space surrounding the part 36 to the tube 29, while the tube 30 is connected 100 110 115 120 125 130

with the outlet opening 39 through the space surrounding the part 37. The relay piston valve is thereby put over to the opposite end position (Fig. 3). The communication from the intermediate vessel 32 to the tube 21 is thereby interrupted by one of the tightening pistons of the relay piston valve and the vessel is instead put in communication with the regulating vessel 24 through the tube 31, the space surrounding the part 44, the groove 47, the space surrounding the part 43 and the tubes 26 and 28. The valve-face 40 now interrupts the communication of the tube 26 with the exterior of the mine through the tube 27. The low pressure air inclosed in the intermediate vessel now rushes over to the regulating vessel, so that an equalizing of the pressure in both of these vessels takes place. A part of the water flowing into the regulating vessel is now expelled again through the tube 25, whereby the displacement of the mine is suddenly increased and consequently the mine rises again toward the surface of the water.

When the mine has risen so much, that the hydrostatic piston, actuated by the spring pressure, has returned to its outermost position, the position of the relay piston valve (Fig. 2) is again reversed, whereby the water again begins to rush in into the regulating vessel 24, thereby expelling the air inclosed in the said vessel through the tube 21. At the same time the intermediate vessel is refilled with low-compressed air from the tube 21. On account of the pouring-in of water, the mine now begins to sink again and the mine will obviously continue to swing around the predetermined middling depth position as long as the pressure in the air vessel is sufficiently high. When, on the contrary, the pressure in said vessel has gone down too far, the mine is not able to keep itself up at the determined depth, but gradually sinks lower and lower, whereby the action of the mine ceases.

For practice purposes a device with a clock-work or such like may, if desired, be placed in the mine and arranged in such a manner that the regulating vessel 24 is filled with air and simultaneously shut off from the communication with the surrounding water after a predetermined time has passed since the laying out of the mine or since the pressure in the air supply vessel has been reduced to a certain amount, whereby the mine will rise to the surface and be saved.

The regulating vessel 24 ought to be so dimensioned that its volume is at least equal to the total amount of the displacement necessary for the reversal of the direction of the movement of the mine and the displacement necessary with regard to the varying specific weight of the water.

If so desired the mine may be provided

with a vessel or cylinder opening outward to the water, said vessel or cylinder being provided with a movable piston or such like for the purpose of determining the displacement of the mine previous to its laying out in the sea.

In order to prevent the mine from taking in too much water in the regulating vessel owing to friction or the like in the parts of the mechanisms, thus causing the mine to sink too low, the tube 28 may, previous to the laying out of the mine, be so adjusted, that only a due part of the volume of the regulating vessel may be filled with water. The water can only rise somewhat above the lower mouth of said tube 28, as the air inclosed in the upper part of the vessel is compressed and soon equalizes the pressure of the incoming water. Should, however, the mine have taken in so much water in the regulating vessel, that the air admitted from the intermediate vessel 32 does not prove sufficient to drive the mine up again, said mine will, however, not remain long in the deep. The low compressed air surrounding the relay piston valve will namely gradually leak into the regulating vessel, whereby more and more water will be expelled and the mine finally rises to the surface. The leaking-in of air into the regulating vessel may also be inadvertently arranged by letting low-compressed air constantly pour in through a separate channel, provided with a small opening, said channel not being controlled by the relay piston valve. By this a greater surety is attained that the mine will not make too lengthy a deep diving. The exhaust-air from the relay piston valve may either be let out into a separate exhaust vessel with a safety-valve for expelling the air into the water, when a certain pressure has been reached in the exhaust vessel, or else the exhaust air may be expelled directly to the interior of the mine body. In the latter case the mine body is preferably provided with a safety valve.

The exhaust air from the relay piston valve as well as from the regulating vessel ought to be conducted into the water in a finely divided state, so as not to betray the presence of the mine in the water by large bubbles. For this purpose the air may also be conducted from the regulating vessel to a separate exhaust vessel, provided with a plurality of apertures for letting out the air, or else the mouth of the tube 27 may be widened and covered with a metal sheeting, through which a plurality of holes have been bored.

It is obvious that the details may be varied in many ways if only the essential of the invention is maintained, *i. e.* that the increase of the displacement of the mine, in order to endow the same with the necessary

rising power is caused by a sudden supply of a predetermined volume of compressed air or gas in the regulating vessel. The volume and the pressure in the intermediate vessel is evidently to be adjusted in such a manner, that the determined volume of air supplied to the regulating vessel is just enough to give the mine a powerful impulse upward without, however, driving 10 the same too far beyond the desired middling-depth.

The greatest advantage of the device described is, that the deep-swingings of the mine will be reduced to a minimum.

15 It is obvious that any other compressed gas than air, *e. g.* carbonic acid, may be used for the regulation of the depth.

Having thus fully described and ascertained the nature of my said invention, 20 what I claim and desire to secure by Letters Patent is:—

1. A floating mine comprising in combination, a regulating vessel, a pressure vessel, an intermediate vessel, connections and 25 valve means for leading air from said pressure vessel to said regulating vessel through said intermediate vessel, and automatic hydrostatic means for controlling the action of said valve means, said valve means and 30 said automatic means being so arranged as to connect said pressure vessel with said intermediate vessel when the mine is above a certain depth and to connect said intermediate vessel with said regulating vessel 35 when the mine is below a certain depth, and being arranged also to cut off said intermediate vessel from said pressure vessel at the time the intermediate vessel is connected to the regulating vessel.

40 2. A floating mine comprising in combination, a regulating vessel, a pressure vessel, an intermediate vessel, connections and valve means for leading air from said pressure vessel to said regulating vessel through 45 said intermediate vessel, and automatic hydrostatic means for controlling the action of said valve means, said valve means and said automatic means being so arranged as to connect said pressure vessel with said intermediate vessel when the mine is above a certain depth and to connect said intermediate vessel with said regulating vessel when the mine is below a certain depth, said valve means including a rapidly actuated 50 piston valve for controlling the inlet and outlet of air from said intermediate vessel, and being arranged also to cut off said intermediate vessel from said pressure vessel at the time the intermediate vessel is connected to the regulating vessel.

3. A floating mine comprising in combination, a regulating vessel, a pressure vessel, an intermediate vessel, connections and valve means for leading air from said pressure vessel to said regulating vessel through

said intermediate vessel, and automatic hydrostatic means for controlling the action of said valve means, said valve means and said automatic means being so arranged as to connect said pressure vessel with said intermediate vessel when the mine is above a certain depth and to connect said intermediate vessel with said regulating vessel when the mine is below a certain depth, said valve means including a rapidly actuated piston valve for controlling the inlet and outlet of air from said intermediate vessel, said piston valve controlling also the said regulating vessel, and being arranged also to cut off said intermediate vessel from said pressure vessel at the time the intermediate vessel is connected to the regulating vessel. 75

4. A floating mine comprising in combination, a regulating vessel, a pressure vessel, an intermediate vessel, connections and valve means for leading air from said pressure vessel to said regulating vessel through said intermediate vessel, and automatic hydrostatic means for controlling the action of said valve means, said valve means and said automatic means being so arranged as to connect said pressure vessel with said intermediate vessel when the mine is above a certain depth and to connect said intermediate vessel with said regulating vessel when the mine is below a certain depth, and being arranged also to cut off said intermediate vessel from said pressure vessel at the time the intermediate vessel is connected to the regulating vessel, said valve means including a rapidly actuated piston valve for controlling the inlet and outlet of air from said intermediate vessel, and means for applying compressed air to said piston valve for moving the same. 85

5. A floating mine comprising in combination, a regulating vessel, a pressure vessel, an intermediate vessel, connections and valve means for leading air from said pressure vessel to said regulating vessel through said intermediate vessel, and automatic hydrostatic means for controlling the action of said valve means, said valve means and said automatic means being so arranged as to connect said pressure vessel with said intermediate vessel when the mine is above a certain depth and to connect said intermediate vessel with said regulating vessel when the mine is below a certain depth, and being arranged also to cut off said intermediate vessel from said pressure vessel at the time the intermediate vessel is connected to the regulating vessel, said valve means including a rapidly actuated piston valve for controlling the inlet and outlet of air from said intermediate vessel, and means for applying compressed air to said piston valve for moving the same, said last mentioned means comprising a second piston valve. 100

6. A floating mine comprising in combi- 115

- nation, a regulating vessel, a pressure vessel, an intermediate vessel, connections and valve means for leading air from said pressure valve to said regulating vessel through said 5 intermediate vessel, and automatic hydrostatic means for controlling the action of said valve means, said valve means and said automatic means being so arranged as to connect said pressure vessel with said intermediate vessel when the mine is above a certain depth and to connect said intermediate vessel with 10 said regulating vessel when the mine is below a certain depth, and being arranged also to cut off said intermediate vessel when the mine is above a certain depth and to connect said intermediate vessel with said regulating vessel when the mine is below a certain depth, and being arranged also to cut off said intermediate vessel 15 when the intermediate vessel is connected to the regulating vessel, said valve means including a piston valve device having a casing and a valve therein provided with two end pistons 20 and two intermediate pistons, there being spaces between the two pistons and grooves in said casing for passing air longitudinally thereof.
7. A floating mine comprising in combination, a regulating vessel, a pressure vessel, an intermediate vessel, connections and 25
- valve means for leading air from said pressure vessel to said regulating vessel through said intermediate vessel, automatic hydrostatic means for controlling said valve 30 means, said valve means and said automatic means being so arranged as to connect said pressure vessel with said intermediate vessel when the mine is above a certain depth and to connect said intermediate vessel with 35 said regulating vessel when the mine is below a certain depth, and being arranged also to cut off said intermediate vessel from said pressure vessel at the time the intermediate vessel is connected to the regulating vessel, 40 and a pressure regulator inserted in the connection between the pressure vessel and the intermediate vessel in order that gas of a certain predetermined reduced pressure may 45 be supplied to the intermediate vessel.

In testimony whereof I have affixed signature in presence of two witnesses.
